UNITED STATES PATENT OFFICE

LOUIS ZWEIG, OF BROOKLYN, NEW YORK, ASSIGNOR TO SUN RISE LAMP MFG. CO., INC.,
A CORPORATION OF NEW YORK

DESIGN FOR A COMBINED LAMP AND CLOCK CASE

Application filed August 16, 1929. Serial No. 32,422. Term of patent 3½ years.

To all whom it may concern:

Be it known that I, LOUIS ZWEIG, a citizen of the United States, and a resident of the city of Brooklyn, county of Kings, and State of New York, have invented a new, original, and ornamental Design for a Combined Lamp and Clock Case, of which the following is a specification, reference being had to the accompanying drawing, forming a part hereof.

In the drawing:

Figure 1 is a perspective view; and
Figure 2 is a combined top plan view and

horizontal sectional view (on line 2—2 of Figure 1) showing the combined lamp and clockcase, characterized by the provision of a central compartment A for a clock, and side compartments B—B for electric lamps C, the lamps being enclosed in glass panels D carried behind columns E in the sides and front.

I claim:

The ornamental design for a combined lamp and clockcase substantially as shown and described.

LOUIS ZWEIG.
